UNITED STATES PATENT OFFICE.

STANLEY B. T. WORDEN, OF NEW YORK, N. Y.

HOLDER.

Application filed March 6, 1920. Serial No. 363,735.

To all whom it may concern:

Be it known that I, STANLEY B. T. WORDEN, a citizen of the United States, and a resident of the city of New York, county of Bronx, and State of New York, have invented an Improvement in Holders, of which the following is a specification.

This invention relates to holders for containers and more particularly to holders for such collapsible tubular containers as are usually provided for tooth paste, shaving cream, and like substances.

One of the objects of this invention is to provide a simple and practical holder to which a collapsible tube or container may be readily secured and which will permit of an easy and convenient manipulation in manually ejecting the contents of the container. Other objects will be in part obvious or in part pointed out hereinafter.

In the accompanying drawings in which is shown a preferred embodiment of this invention for purposes of illustration,

Figure 1 is a plan view,

Figure 2 is a side elevation partly in section of a holder illustrative of this invention,

Figures 3 and 4 are respectively right and left hand end views,

Figures 5 and 6 are respectively a view in plan and a side elevation showing a holder as applied to a collapsible tubular container.

Referring to the drawings and particularly to Figures 1 and 2 there is shown a holder comprising a main supporting member 10 made preferably of sheet metal and shaped to conform substantially to the contour of a collapsible tubular container 11 as shown in Figures 5 and 6. The main frame member 10 is substantially flat at its right hand end portion from which it gradually tapers toward its left hand end to a slightly less effective width than the width at its right hand end portion. The member 10, in addition to having its effective width decreased slightly in the direction from its right hand end to its left hand end, is formed into upwardly extending side portions, the member 10 varying in its cross

section from substantially a straight line at its right hand end to substantially a semi-circle at its left hand end. The main member is thus nearly conformed to the contour of a substantial portion of the container 11.

At its right hand end the member 10 is provided with up-turned lips 12 and 13,

preferably integral therewith, more clearly shown in Figure 3, and adjacent the lips 12 and 13 the member 10 is cut away or recessed as at 14 and 15 for a purpose to be herein-
after described.

At its left hand end, which end is substantially semi-circular in section, there is provided an up-turned end portion 16, more clearly shown in Figures 3 and 4, this end portion being provided at substantially its center with an aperture 17 preferably counter-sunk from the inside to provide a circular knife edge 18. The end member 16 may be made integrally with the main supporting member 10 or may be made separately and suitably secured to the end of the member 10 by soldering or by any convenient method. The end member 16 tapers outwardly from the central portion in which the aperture 18 is made to the semi-circular left hand end portion of the member 10. The taper of the end portion 16 is preferably made substantially similar to the taper of the end portion 19 of the container 11. The main member 10 may be readily stamped out of sheet metal and formed in the manner hereinbefore described, the lips 12 and 13 being bent inwardly as is more clearly shown in Figure 3. If desired the right hand end portion of the member 10 may be provided with an aperture 20 which may be made in an extension of the member 10 for a purpose to be hereinafter made clear.

The container 11 is of the usual collapsible tubular construction generally provided for substances like tooth paste, for example, and at one end thereof is closed by a clamping member 21 at which end the container 11 tapers down to a substantially flattened end 95 or straight line. Approaching its opposite end the container 11 gradually tapers into a substantially cylindrical shape at the end of which it terminates in the tapered end portion 19 which in turn terminates in a threaded tubular extension 22 of reduced diameter. The tubular extension 22 provides an exit for the material within the container and upon its threaded portion is adapted to receive a cap 23.

The container 11 is first slightly flattened on the under side to present a substantially straight line lower edge to conform substantially with the center line of the main supporting member 10. The cap 23 is thereupon removed from the container 11 and the container inserted into the holder,

the flattened end portion 21 being inserted under the over-turned lips 12 and 13 whereby the end portion is held in slidably engagement with the main member 10. The 5 container 11 is then moved to the left with respect to the main member 10 to permit the tubular extension 22 to be aligned with the opening or aperture 17 in the end member 16. Movement to the left with respect 10 to the main member 10 is thereupon given to the container 11, the threaded tubular extension 22 entering the aperture 17 and the knife edge 18 of the counter-sunk or tapered aperture 17 engaging the threaded portion 15 of the extension 22. The container 11 is thus securely positioned within the holder, the up-turned end portion 16 with its associated apertures 17 and knife edge 18 locking the container 11 against both longitudinal and lateral movement with respect to 20 the holder itself. The member 10, being conformed or shaped to the contour of the lower or under part of the container 11, provides a substantial support therefor and 25 provides for a continuous support for the container 11 against which pressure may be exerted to collapse the container 11 to cause its contents to be emitted from the tubular extension 22. Preferably the pressure is 30 applied first at the right hand or flattened end of the container and is applied progressively toward the left hand end as the contents of the container is diminished.

In manipulating a collapsible tubular container such as the container 11, the material 35 coming out of the tubular extension 22 is oftentimes extended to a greater length than is desired the emission continuing after release of pressure upon the container and in 40 order to prevent the waste of such superfluously emitted material, the container 11 may be depressed at one or both of its lateral portions exposed by the recesses 14 and 15, such depression causing the flattened end 45 portion to be raised slightly, thus increasing the interior volume of the container. Such increase in volume will be met by a withdrawal by atmospheric pressure into the container 11 of the excessive amount of

material extending through the tube 22. 50 The recesses 14 and 15 are preferably made of such dimensions that they will each readily accommodate a finger of the hand for laterally depressing the flattened end portion of the container. 55

The cap 23, after use has been made of the holder and container, may be replaced and screwed upon the threaded tubular extension 22, thus not only closing the tube 11 but also securely locking the container 60 to the holder. The holder and its container may thereupon be hung up on a hook or pin which is received by the aperture 20 in the main supporting member 10.

As various possible embodiments may be 65 made in the above invention and as various changes might be made in the embodiment above set forth, it is to be understood that all matter herein set forth or shown in the accompanying drawings is to be interpreted 70 as illustrative and not in a limiting sense.

I claim as my invention:

In a device of the class described, in combination, a substantially cylindrical container having a substantially flattened closed end and having its opposite and cylindrical end provided with an externally threaded tubular extension of reduced diameter, a supporting frame member of substantially the same length as said container shaped to fit closely against one side of and encase one half of said container, having inwardly bent lugs at one end for engaging the flattened end of said container permitting relative longitudinal movement 85 while preventing relative lateral movement between said container, and said member and having recesses adjacent said lugs to give access to the edges of the container, said frame member having at its opposite end an upturned portion for interlocking with the threaded extension, substantially 90 as and for the purpose described.

In testimony whereof, I have signed my name to this specification this 3rd day of 95 March, 1920.

STANLEY B. T. WORDEN.
